UNITED STATES PATENT OFFICE

101,104

DESIGN FOR A COMBINED WINDOW SHADE, CURTAIN, AND DRAPERY SUPPORT

William Bushey and Ernest Henry Bushey,
Plattsburg, N. Y.

Application July 28, 1936, Serial No. 64,108

Term of patent 7 years

To all whom it may concern:

Be it known that we, William Bushey and Ernest Henry Bushey, citizens of the United States of America, residing at Plattsburg, in the county of Clinton and State of New York, have invented a new, original, and ornamental Design for a Combined Window Shade, Curtain and Drapery Support, of which the following is a specification, reference being had to the accompanying drawing, forming part thereof.

The figure is a perspective view of a combined window shade, curtain and drapery support, showing my new design.

We claim:

The ornamental design for a combined window shade, curtain and drapery support, as shown.

WILLIAM BUSHEY.
ERNEST HENRY BUSHEY.
